UNITED STATES PATENT OFFICE.

ROBERT H. HOLDAWAY, OF CONRAN, MISSOURI.

RAIL-JOINT.

1,179,312.

Specification of Letters Patent. Patented Apr. 11, 1916.

Application filed January 4, 1916. Serial No. 70,148.

To all whom it may concern:

Be it known that I, ROBERT H. HOLDAWAY, a citizen of the United States, residing at Conran, in the county of New Madrid and State of Missouri, have invented new and useful Improvements in Rail-Joints, of which the following is a specification.

This invention relates to improvements in joints for railway rails and the like, the object of the invention being to effect improvements in the construction of the ends of railway track rails so that a joint may be readily formed between them which will prevent the rail ends from pounding or moving vertically, unevenly, under the weight of passing trains and will also prevent the rails from spreading and from moving lengthwise.

The invention consists in the construction, combination, and arrangement of devices hereinafter described and claimed.

In the accompanying drawings:—Figure 1 is a perspective of the meeting ends of a pair of rails joined in accordance with my invention. Fig. 2 is a similar view of one rail end. Fig. 3 is a detail perspective view of the other rail end. Fig. 4 is a vertical transverse sectional view on the plane indicated on the line A—A of Fig. 1. Fig. 5 is a similar view on the plane indicated on the line B—B of Fig. 1.

The rails 1 may be of any suitable construction and each is here shown as having a base 2, a web 3 and a head 4.

In accordance with my invention, each rail is formed at the ends with an extension 5 which, at one end of one of the rails, is at the base thereof and at the meeting end 40 of the other rail is at the head thereof, so that the said extensions are arranged in overlapping relation to form a joint between the rails, as shown in Fig. 1. Each rail is provided at one end with a longitudinal horizontal recess 6 and its extension is provided at the outer end with a corresponding projection 7 to fit in the recess 6 of the meeting rail, said recesses and projections locking the rail ends and preventing them from pounding or moving ver-

tically independently of each other under the weight of passing trains. Each extension is also formed, near the outer end, with an upwardly extending projection 8 and is also formed near one end with a downwardly extending recess 9 to receive the projection 8 of the opposing rail end. These recesses and projections lock the rail ends together against longitudinal movement.

The rail ends are respectively provided with lugs 10, 10^a, each lug being at a point about mid-way between the ends of the rail extension and being on one side thereof. The lug 10 extends upwardly from the base extension of one rail to bear on one side of the extension of the meeting rail and the lug 10^a extends downwardly from the head extension of the meeting rail and extends to and is shaped to conform to the base thereof as shown and is on the side opposite the lug 10. These lugs are, in practice, preferably integral with the respective rails and are rolled therewith. When the rail ends are spiked to the ties, the lugs 10, 10^a prevent the rails from spreading. The joint thus formed between the rail ends is exceedingly strong and I entirely avoid the use of bolts and fish plates for securing the rail ends together. The rail ends are readily interengaged to form a joint between them and may be readily unjoined after the spikes have been withdrawn.

While I have herein shown and described a preferred form of my invention, I would have it understood that changes may be made in the form, proportion, and construction of the several parts without departing from the spirit of the invention and within the scope of the appended claim.

Having described the invention what is claimed is:

In a rail joint, a pair of rails, one having a head extension and the other having a base extension, said head extension bearing on the base extension and having a downwardly extending lug bearing against one side of the base extension, said base extension having an upwardly extending lug bearing against the other side of the head extension, each rail also having a vertical

recess in its extension and a vertical projection on its extension to enter the vertical recess of the other rail extension, and each rail also having a transverse longitudinal recess in one end, and a corresponding projection at the other end of its extension to enter said recess of the other rail.

In testimony whereof I affix my signature in presence of two witnesses.

ROBERT H. HOLDAWAY.
